UNITED STATES PATENT OFFICE.

ALMON M. GRANGER, OF MEDFORD, MASSACHUSETTS.

AUTOMATIC FIRE-EXTINGUISHING APPARATUS.

SPECIFICATION forming part of Letters Patent No. 367,390, dated August 2, 1887.

Application filed April 25, 1885. Serial No. 163,423. (No model.)

To all whom it may concern:

Be it known that I, ALMON M. GRANGER, of Medford, in the county of Middlesex and State of Massachusetts, have invented certain new and useful Improvements in Automatic Fire-Extinguishing Apparatus, of which the following is a specification.

This invention has for its object to provide improved means for excluding water from a system of automatic sprinkler-pipes until it is required for use, and then to admit it automatically to the pipes and permit it to find its way quickly to the points of discharge.

To these ends the invention consists as a whole in an automatic sprinkler system or apparatus consisting of a pipe or pipes having sprinklers the valves of which are held closed by fusible fastenings and are automatically opened when said fastenings are released, means for exhausting the air from said pipes, an automatically-opening valve which is held by a retaining device to exclude water from said pipes and maintain a vacuum therein, and a diaphragm or piston which is held by atmospheric pressure while said vacuum is maintained, and means, hereinafter described, which are held by the diaphragm, and upon the release of the latter by the partial breaking of the vacuum release the valve and allow it to admit water to the pipes and sprinklers.

The invention also consists in an automatic trap which is operated by the water entering the sprinkler-pipes to disconnect them from the air-exhausting apparatus.

The invention also consists in certain details, all of which I will now proceed to describe and claim.

Of the accompanying drawings, forming a part of this specification, Figure 1 represents an elevation of apparatus embodying my invention. Fig. 2 represents a different elevation of the valve controlling the admission of water to the sprinkler-pipes and its operating devices. Fig. 3 represents a section on line xx , Fig. 2. Fig. 4 represents a sectional view of the automatic trap. Fig. 5 represents a sectional view of one of the automatic sprinklers. Fig. 6 represents a sectional view of the diaphragm-chamber.

The same letters of reference indicate the same parts in all the figures.

In the drawings, a represents a main con-

ducting-pipe communicating with a suitable system or series of branch-pipes, a' , which are provided with automatic sprinklers b , hereinafter described, said pipes a' being located in any suitable part of an apartment or building to be protected, while the pipe a communicates with a source of water-supply. At a suitable point in the pipe a is a valve, c , 55 adapted to shut off or admit the water. The stem c' of said valve is provided with a drum or pulley, d , on which is wound a cord or chain, e , having a weight, f , which, when free to act, rotates the valve, so as to open it and 60 admit water to the sprinkler-pipes a' .

g represents an air-pipe communicating with the pipe a between the valve c and the sprinklers, said pipe being connected with an air-exhausting apparatus—such as a steam-ejector, 70 E , or other apparatus—whereby air may be exhausted from the pipes a a' . A vacuum-pump, h , may also be provided for use in emergencies. With the pipe g is connected a chamber, i , having for its bottom a flexible diaphragm, i' . Said diaphragm supports a weighted rod, j , having a shoulder or collar, j' . When the air is exhausted from the pipes a a' the diaphragm is raised, as shown in Figs. 1 and 75 6, by atmospheric pressure, and holds the rod j in a raised position. When air is admitted into said pipes and the so called "vacuum" is partially broken, as hereinafter described, the diaphragm i' and rod j fall, and the shoulder j' strikes the rear end of a pivoted dog or 80 pawl, k , which is engaged with a ratchet, l , on the valve-stem c' , to hold the valve closed, and disengages said dog from the ratchet, whereupon the weight f falls and rotates the valve, 85 thus admitting water to the pipes a a' . The admission of air into the pipes a a' is effected 90 by the opening of one or more of the sprinkler-valves caused by a rise in the temperature in the neighborhood of such sprinkler or sprinklers. Each sprinkler has a nozzle, m , 95 connected to a pipe, a' , and a valve, n , which is normally held against the nozzle by holding devices secured by a fastening that fuses at a comparatively low degree of heat. The valve is provided with a spring, o , which forces it 100 away from the nozzle when the fusible fastening gives way, thus preventing the valve from adhering to its seat by atmospheric pressure resulting from the vacuum in the pipes. Said

spring is here shown as placed upon a rod, which slides in a bridge or guide in the nozzle and bears against the valve, the spring bearing at one end on a shoulder on the rod and at the other on a guide. In the present instance I have shown the valve supported by a stud, *p*, bearing on a lever, *q*, which is pivoted to the frame of the sprinkler, and is secured thereto at its outer end by a link, *r*, of fusible metal. 10 When said link is ruptured by heat, the lever and stud drop, and the spring *o* forces the valve down with the stud.

It will be seen that when the valve *e* is closed and the air is exhausted from the pipes the 15 conditions are favorable for the quick opening of the valve and the rapid flow of water through the pipes, the movement of the incoming water being facilitated by the degree of vacuum in the pipes. The pipes may therefore be kept empty until their use is required, 20 thus avoiding danger of clogging and bursting by the freezing of the water in cold weather, as well as the rust and corrosion which attend the long-continued presence of water in iron 25 pipes.

To prevent the water from passing into the air-pipe *g* when admitted to the pipes *a a'*, I provide a trap consisting of a casing, *s*, communicating with both the pipe *a* and the air-pipe, the connection with the pipe *a* being 30 with the lower portion of the casing while the air-pipe communicates with its upper portion, as shown in Figs. 1 and 4. Within the casing is a pivoted valve, *t*, to which is attached a 35 float-lever, *u*. When a small quantity of water (not enough to reach the air-pipe *g*) has accumulated in the casing *s*, the float rises and closes the valve *t* against the end of the passage *v* from the pipe *a*, thus shutting off the 40 water and preventing it from reaching the air-exhausting apparatus. The water thus accumulating in the casing *s* may be released by a cock, *w*.

y represents a stand pipe, thirty-two feet or 45 less in height, connected at its upper end by a pipe, *y'*, with the air-pipe *g*, and adapted to contain a column of water. When the air is exhausted from the pipes *a a'*, said column, supported by atmospheric pressure, acts as an 50 exhausting-piston having a constant tendency to maintain the vacuum in the pipes *a a'*, or, in other words, to keep a uniform degree of vacuum in said pipes, any small quantities of air admitted to the pipes by leakage being 55 prevented by said water column from decreasing the vacuum sufficiently to cause the release of the diaphragm. The pipe is provided near its upper end with a reservoir or enlargement, *y''*, which prevents the height of the column 60 from being too rapidly decreased by the introduction of air by leakage.

The exhausting-pressure exerted by the column of water on the sprinkler system of piping is directly proportioned to the height of the column, said pressure being one pound for every two feet of the height of the column. 65 The enlargement or reservoir enables a con-

siderable introduction of air by leakage before the height of the column is so reduced that it is incapable of maintaining the degree of rarification in the pipes *a a'* required to hold the diaphragm in its raised position. 70

The height of the water column is preferably twenty-eight feet when the air is first exhausted from the pipes *a a'*, thus giving an 75 exhausting-pressure of fourteen pounds. I prefer to weight the diaphragm *i*, so that it will fall when the water falls two feet in the reservoir, thus reducing the exhausting-pressure of the water column to thirteen pounds. 80

The capacity of the reservoir *y''* is such that a considerable length of time will be required for the admission of air by leakage in sufficient quantity to cause the above specified reduction in the height of the column, so that if the 85 vacuum-gage *g'*, connected with the air-pipe, be watched and care be taken to exhaust the air as the pressure becomes reduced by leakage, danger of the admission of water to the pipes when the need thereof does not exist will 90 be avoided. The quantity of air admitted by the opening of one or more of the sprinkler-valves is sufficient, however, to immediately cause the required reduction in the height of the water-column without wholly breaking 95 the vacuum in the sprinkler system, the trap being closed by the entering water, thus disconnecting the stand-pipe from the system of sprinkler-pipes, leaving them in a state of partial vacuum, so that the water enters them 100 more readily than if they contained air under ordinary atmospheric pressure.

The pipe *y'*, which connects the stand-pipe with the air-pipe *g*, should extend upwardly above the height which the water-column can 105 attain, so that the water cannot be drawn from the stand-pipe through the pipe *y'*.

T represents a tank communicating with the lower end of the stand-pipe and receiving water therefrom when the column falls, and 110 supplying water to raise the column.

If desired, the air may be exhausted from the pipes *a a'* by first filling the reservoir *y''* with water and then allowing it to fall through the stand-pipe, the water in falling acting as 115 an exhausting-piston. In this case the stand-pipe should have a valve at *V* to retain the water in the reservoir until it is filled, and the reservoir should have a valved water-supply pipe, *P*, and a vent for the escape of air while 120 it is being filled. The hub of the pulley *d* has a screw or stud, *d'*, projecting into a slot, *c'*, extending partly around the valve-stem *c*. (See Fig. 3.) When the valve is closed, the stud *d* is at the upper end of said slot, as shown, 125 but when the pulley is released the slot enables the pulley to be partially rotated before it strikes the other end of the slot *c'* and moves the valve with it. The weight thus acquires sufficient impetus to cause the stud *d'* 130 to strike the end of the slot with considerable force, and thus insure the starting of the valve in case it sticks to its seat or casing.

Water may be raised in the stand-pipe by

the condensation of steam in the enlargement or reservoir y^2 , steam being admitted to the reservoir and condensed therein, thus forming a vacuum which will raise the water to the required height. In this case a check-valve, V^2 , should be provided in the pipe y' to prevent the steam from entering and heating the sprinkler-pipes so as to rupture the valve-holding links.

10. I claim—

1. An automatic sprinkler system or apparatus consisting of a pipe or pipes having sprinklers the valves of which are closed by fusible fastenings and are automatically opened 15 when said fastenings are released, means for exhausting the air from said pipes, an automatically-opening valve which is held by a retaining device to exclude water from said pipes and maintain a vacuum therein, and a 20 diaphragm or piston which is held by atmospheric pressure while said vacuum is maintained, and means, substantially as described, which are held by the diaphragm, and upon the release of the latter by the breaking of the 25 vacuum release the valve and allow it to admit water to the pipes, as set forth.

2. The combination, with an automatic sprinkler pipe or pipes and means for exhausting air therefrom, of an automatically-opening 30 valve which controls the admission of water to said pipes, locking devices held by atmospheric pressure to keep said valve closed while a vacuum is maintained in said pipes, and a trap which is operated by water entering said 35 sprinkler-pipes to shut off the connection between said sprinkler-pipes and the air-exhausting apparatus when the vacuum is broken, as set forth.

3. The stand-pipe connected to the automatic 40 sprinkler-pipes and provided with a reservoir or enlargement at or near its upper end, as set forth.

4. The combination, with the main sprinkler-

supply pipe having a valve provided with an automatic opening device, of an air-pipe connecting said pipe with an air-exhausting apparatus, a chamber having a flexible diaphragm connected with said air-pipe, a dog engaged with a ratchet on the stem of the valve to hold the latter closed, and a weighted rod connected 45 with said diaphragm and held in suspension by atmospheric pressure thereon while the vacuum is maintained and allowed to fall and release the valve when the vacuum is broken, as set forth.

5. The combination, with the automatic sprinkler-pipe and the valve holding and releasing devices, of the rotary valve having on its arbor the weighted drum or pulley which is free to make a partial independent rotation 50 before engaging and rotating said stem, substantially as and for the purpose specified.

6. The combination of a series of water-supply pipe or pipes having automatic sprinklers, means for exhausting air from said pipes, a 55 weighted diaphragm supported by atmospheric pressure when the air is exhausted from said pipes and allowed to fall by the admission of air in given quantity to said pipes, a valve in the main water-supply pipe, provided with 60 an automatic opening device which is held to keep the valve closed by a detent controlled by said diaphragm, and a stand-pipe containing a column of water which acts as an exhausting-piston to maintain the vacuum in the pipes 75 and to support the diaphragm until a given reduction in the height of the column is caused by the introduction of air into the water-supply pipes, as set forth.

In testimony whereof I have signed my name 80 to this specification, in the presence of two subscribing witnesses, this 21st day of April, 1885.

ALMON M. GRANGER.
